(57) **CLAIM**

The ornamental design for a table, as shown and described.

DESCRIPTION

FIG. 1 is a left front perspective view of a table showing my new design;

FIG. 2 is a front elevational view thereof;

FIG. 3 is a side elevational view, the opposite side being a mirror image thereof;

FIG. 4 is a rear elevational view thereof; and,

FIG. 5 is a top view thereof.

The views of the table not shown form no part of the claimed design. The dashed lines in FIGS. 1-4 depicting stitching represent environmental elements only and form no part of the claimed design. The broken lines in FIGS. 1, 2, 3, and 5 depicting hardware represent environmental elements only and form no part of the claimed design. The broken lines in FIG. 5 depicting the center design represent environmental elements only and form no part of the claimed design.

1 Claim, 5 Drawing Sheets
